UNITED STATES PATENT OFFICE

JOHN SCHLEINZER, OF ROCHESTER, NEW YORK

INDICATING ATTACHMENT FOR TYPEWRITERS

Application filed March 28, 1928. Serial No. 265,455.

The object of this invention is to provide a new and useful attachment for typewriters by which a signal will be given when the operator has written on a line that is near 5 the bottom or near a predetermined point on the sheet.

Another object of this invention is to cause the device that feeds the paper through the machine to ring a bell and thus give a 10 signal when a predetermined length of the paper has been fed through the machine.

This and other objects of the invention are fully illustrated in the drawings.

In the drawing:

15 Figure 1 is a side elevation of my improved attachment as it appears on the carriage of the typewriter.

Figure 2 is a top plan view of my improved attachment to the carriage of the 20 typewriter as shown in Figure 1.

In the drawings reference numeral 1 indicates the end frame of the carriage of the typewriter, 2 indicates the platen roller that feeds the paper in the typewriter and 3 indicates the shaft that carries this roller. 25 On this roller is provided a pinion 4 which meshes with the rack 5 carried in a guide sleeve 6. As the roller is turned to feed the paper, the rack moves forward being driven by the pinion 4. On the left hand end of the rack as shown in Figure 1 is provided a lug 7. The rack sleeve is supported from a bracket 8 which in turn is pivotally mounted on the end frame, the pivot 9 being 30 provided for this purpose. This bracket is offset at 10 as indicated in Figure 1 to form a ledge or shoulder that can be engaged by the locking pawl 12 which is pivotally mounted on the frame at 13. As long as the 40 rack is in the position shown in Figure 1 it engages the pinion 4 and is moved thereby. It is held in this position by a spring pressed pin 14 mounted in a sleeve 15 which is carried on the end frame of the carriage. When 45 it is desired to throw this attachment out of operation, the operator pushes down on the lug 7 and rocks the sleeve and rack on the pivot 9 pushing up on the pin 14 in so doing.

While in this position the pawl 12 can be 50 swung forward at the bottom to engage with

the shoulder 10 and lock the rack with its forward end in elevated position. The pawl 12 is cam shaped at the lower right hand corner so that the movement of the pawl 12 will of itself swing the rack to the idle 55 position. As the roller 2 turns when the rack is in active position, it is driven out to the right as shown in Figure 1 and at the end of its movement is in an extended position. A spring 16 is provided which at its 60 right hand end in Figure 2 is attached to the pin 17 carried on the rack and at the left hand end is attached to the pin 18 provided on the sleeve 6. By pushing down on the lug 7 when the rack is in extended position 65 or partly extended, the rack is disengaged from the pinion 4 and the spring 16 contracts to pull the rack back at once to its normal position in the sleeve.

On the end frame of the carriage is provided a stationary guide bar 20. On this is mounted a slide 21 on which is carried a bell 22 which is provided with a hammer 23 and a trigger 24. When the rack 5 is extended the offset lug 28 on the end of it engages with the pawl 26 on trigger 24 which causes the hammer to raise to a certain point where it passes the pawl when it is released and is then drawn down by the spring 25 which causes the hammer to strike the bell 22 and ring it, and the bell is thus rung whenever the rack has moved past the predetermined point. The trigger 24 is provided on the bottom with a pawl 26 pivoted at 27. The pawl and trigger all move together 70 when the rack moves to the right until the lug 28 on the rack has passed beyond the pawl 26. Then the hammer drops and at the rearward movement of the rack the pawl 26 can yield and permit the lug 28 to pass 75 thereunder.

As shown in Fig. 2 the movable slide 21 is provided with a pointer 31 which points to marks on the stationary scale 32. The slide and the bell can be shifted and its position will be indicated on the scale, and this will indicate whether the rack will engage it after a long movement or a short movement. On the side of the stationary guide 80 20 are provided recesses 33 with which en- 85

gages the spring pressed pin 34 carried on the slide 21 and by which it is positively stopped in the various positions indicated by the marks on the scale 32.

5 By the use of this device the operator can set the signal on the gauge 32 to correspond to the length of the sheet being used, and the signal will then show the operator that she is near the bottom of the page or at the desired point where the letter must be stopped on that page so that she can then remove the sheet from the machine without looking at it. This will enable the operator to make the several pages of the letter with uniform 15 margins at the bottom without having to pay any especial attention thereto.

10 The rack 5 is mutilated near both ends so that when it comes to the end of its movement in either direction it will on that account stop and cannot be forced by turning the platen by hand. This provision is made so as to make it impossible to strip the teeth from either the rack or the pinion.

15 The sleeve 6 at the left hand end of Figure 1 is provided with a spring 40 which acts as a cushion in stopping the return movement of the rack due to the contracting of the spring 16. This spring cushion 40 also permits the rack to yield when the platen is turned by hand so that in this way the stripping of a tooth is prevented, and when released it throws the rack forward so as to make engagement with the pinion.

20 It has also been found desirable to make each of the teeth of the pinion 4 formed with an edge on top rather than a broad surface so as to avoid dead centering the teeth of the pinion and the teeth of the rack.

25 It will also be observed that when the rack is in an extended position with the mutilated part of the rack above the pinion the finished sheet may be removed from the machine in the usual way without disturbing the position of the rack. Thereafter the next sheet can be inserted in the machine by turning the platen in the same direction without disturbing the extended position of the rack. When the sheet is in approximately the correct position, the operator pushes down on the lug 7 which will cause the rack 30 to be disengaged from the pinion so that it can be drawn back into normal position by the spring in which position the other mutilated portion of the rack will be over the pinion permitting the platen to be turned in the reverse direction to bring the paper to the correct starting position without disturbing the starting position of the rack.

35 I claim:

40 1. In a typewriter carriage, the combination of an end frame, a shaft mounted to rotate therein, a roller platen carried by said shaft, a pinion on said shaft, a guide sleeve mounted to rock on said frame, a rack mounted to slide in and out of said guide sleeve,

45 spring pressed means carried by said frame and engaging said sleeve to rock said sleeve in one direction and hold said rack yieldingly in mesh with said pinion, a locking pawl pivoted on said frame and adapted to rock said sleeve in the opposite direction against the pressure of said spring pressed means and hold said rack out of mesh with said pinion. 79

50 2. In a typewriter carriage, the combination of an end frame, a shaft mounted to rotate therein, a roller platen carried by said shaft, a pinion on said shaft, a guide sleeve mounted to rock on said frame, a rack mounted to slide in and out of said guide sleeve, 75 spring pressed means carried by said frame and engaging said sleeve to rock said sleeve in one direction and hold said rack yieldingly in mesh with said pinion, a locking pawl pivoted on said frame and adapted to rock said sleeve in the opposite direction against the pressure of said spring pressed means and hold said rack out of mesh with said pinion, 80 a spring connected to said rack and adapted to return said rack to its starting position when said rack is swung out of mesh with said pinion, a cushioning member in said guide sleeve to cushion the return movement of said rack into said guide sleeve and yieldingly hold the first tooth of said rack in mesh with said pinion when held in contact therewith. 85

55 3. In a typewriter carriage, the combination of an end frame, a shaft mounted to rotate therein, a roller platen carried by said shaft, a pinion on said shaft, a guide sleeve mounted to rock on said frame, a rack mounted to slide in and out of said guide sleeve, 90 spring pressed means carried by said frame and engaging said sleeve to rock said sleeve in one direction and hold said rack yieldingly in mesh with said pinion, a locking pawl pivoted on said frame and adapted to rock said sleeve in the opposite direction against the pressure of said spring pressed means and hold said rack out of mesh with said pinion, 95 a guide bar carried by said frame, a signal mounted to slide on said guide bar, yielding means carried by said signal and projecting into the path of the rack on the movement thereof in one direction, said means operating said signal on the movement of the end of said rack past said means. 100

60 In testimony whereof I affix my signature. 105
